UNITED STATES PATENT OFFICE.

JOHN C. COLLETT, OF DAYTON, OHIO.

CARBURETER

1,095,384.

Specification of Letters Patent.

Patented May 5, 1914.

Application filed May 8, 1913. Serial No. 768,314.

To all whom it may concern:

Be it known that I, JOHN C. COLLETT, citizen of the United States, residing at Dayton, in the county of Montgomery and State 5 of Ohio, have invented certain new and useful improvements in Carbureters; and I do declare the following to be a full, clear, and exact description of the invention, such as will enable others skilled in the art to which 10 it appertains to make and use the same, reference being had to the accompanying drawings, and to the letters and figures of reference marked thereon, which form a part of this specification.

15 This invention relates to new and useful improvements in carbureters of the type adapted to utilize a fuel having a high point of volatilization, such as alcohol, kerosene or various fuel mixtures. In carbureters of 20 this type, the heat of the engine is utilized in evaporating the fuel, and it is therefore necessary to provide a fuel with a low point of volatilization, such as gasoline, to initially start the engine.

25 The object of the present invention is, therefore, to provide a carbureter of simple construction which has a capacity for effectually utilizing fuels of different degrees of volatilization.

30 Another object of the invention is to provide means for increasing the float level of the fuel in the carbureter when the engine is started, thereby priming the carbureter and insuring a sufficiently richer mixture for 35 starting purposes.

The accompanying drawing is a vertical longitudinal sectional view of a carbureter constructed according to my invention.

Referring more particularly to said drawing, 1 represents a shell having a float chamber 2 and an air passage 3, separated by a wall 4, which, together with a wall 5, forms a chamber 6 in which the fuel mixture is prepared. Mounted in said mixing chamber 6 is a fuel jet 7 which is controlled by a needle valve 8 and is adapted to receive oil from the float chamber 2 through a tubular extension 9. The oil enters the chamber 2 through a passage 10 which communicates 45 with a pipe 11, leading from a reservoir (not shown) through a port 12. The port 12 is controlled by a valve 13 which is connected to a float 14 by a lever 15 pivoted at 16. The oil flows through the pipe 11 and 50 the height of the oil in the float chamber 2 is maintained at a constant level by the

valve 13 and float 14 in a well known manner.

Mounted on the shell 1 is a shell 17 which provides a passage 18 which connects the 60 mixing chamber 6 with the manifold of the engine (not shown). The passage 18 is provided with a throttle valve 19, while the mixing chamber 6 is provided with an automatic air valve 20 controlled by a spring 21. 65

The passage 3 receives air, the temperature of which has been elevated by the engine through any well known means, such as a jacket on the exhaust manifold.

To secure an excessively rich mixture for 70 use in starting the engine, the valve or space controller 20 may be depressed against the tension of a spring 22 to reduce the air space by a yoke 23, and a valve 24 mounted in the air passage 3. These elements, however, do 75 not form part of the present invention.

It will be understood that any of the well known types of single fuel carbureters are suitable for use in connection with my invention.

80 The fuel fed to the float chamber 2 may be alcohol, kerosene or any fuel mixture which will not evaporate without the application of heat. A fuel with a low point of volatilization is introduced to the jet 7 by the following means. Tapped into the shell 1, directly below the tubs 9 and jet 7 and discharging into the float chamber 2, is a T-fitting 25. This fitting is provided with a drain cock 26 and is connected with a tube 90 27 which communicates with a reservoir 28 through exhaust and inlet valves 29 and 30 of a pump 31. The valves 29 and 30 are mounted in a housing 32 to which the pump is connected and which forms a part thereof. The said pump 31 and housing 32 are mounted for convenience within the reservoir 28. The said reservoir is supplied with a ready vaporizable fuel, such as gasoline, and when the pump is actuated, a portion of 95 the gasoline in the reservoir will be drawn into the pump and discharged into the float chamber 2. The said pump is actuated before the engine is started, and when so actuated, the fuel level in the chamber 2 will be elevated above normal, thereby 100 insuring an excessive amount of exceedingly rich fuel which will overcome the condensing effect of the cool manifold. Also, as the T-fitting 25 is mounted directly below the 105 jet 7, the fuel initially received by the jet and converted into the fuel mixture in the

chamber 6, will be the fuel having the lower point of volatilization, thereby permitting the engine to start easily. The amount of fuel injected into the float chamber 2, by the pump, is sufficient to operate the engine a desired length of time to permit said engine to develop the heat necessary to volatilize the heavier fuel.

Having described my invention, I claim:

13. 1. In a device of the type specified, the combination with a carbureter having an oil chamber, an air chamber, an intervening mixing chamber, and a jet communicating with the oil chamber and the mixing chamber, an oil reservoir, of a pump having an inlet and an outlet valve, the inlet valve lying on the interior of the said oil reservoir and the outlet valve being exterior to said reservoir, and a pipe connection between the said outlet valve and the float chamber below and in proximity to the jet.

2. In a device of the type specified, the combination with a carbureter having an oil chamber, an air chamber and a mixing chamber, and a jet communicating with said oil and mixing chambers, of an oil reservoir, a pump having a valve-controlled communication with said reservoir, and a valve-controlled communication with the oil chamber of the carbureter, said last named communication being adapted to discharge oil from said reservoir to said jet, whereby a richer fuel may be supplied to the jet of the carbureter at predetermined times, substantially as specified. 35

In testimony whereof I affix my signature, in presence of two witnesses.

JOHN C. COLLETT.
